UNITED STATES PATENT OFFICE.

FREDERICK B. SCHULTZ, OF NEW YORK, N. Y.

DOLL.

1,232,856.

Specification of Letters Patent. Patented July 10, 1917.

Application filed October 17, 1916. Serial No. 126,083.

To all whom it may concern:

Be it known that I, FREDERICK B. SCHULTZ, a citizen of the United States, and a resident of the city of New York, borough of 5 Manhattan, in the county and State of New York, have invented a new and Improved Doll, of which the following is a full, clear, and exact description.

This invention relates to dolls, and has 10 to deal particularly with means for joining the arms, legs and head to the trunk.

The invention has for its general objects to improve and simplify the construction of articles of this character so as to be 15 durable and substantial, comparatively inexpensive to manufacture, and so designed that persons of ordinary skill can readily repair the doll.

A more specific object of the invention is 20 the provision of a novel joint between the members of the doll and the trunk, the joint involving an elastic band which extends entirely through the trunk from one leg to the other, or from one arm to the other, and 25 engaging with the ends of the elastic loop are button-like fasteners having open shanks which are easily and quickly hooked into engagement with the ends of the loop, the buttons being disposed outside the limbs 30 so as to be readily attached or detached.

A further object is to improve the connection of the head with the trunk by means of a hook on the head which engages with the leg or arm-attaching elastic loop.

35 With such objects in view, and others which will appear as the description proceeds, the invention comprises various novel features of construction and arrangement of parts which will be set forth with particularity in the following description and 40 claims appended hereto.

In the accompanying drawing, which 45 illustrates one embodiment of the invention and wherein similar characters of reference indicate corresponding parts in both the views.

Figure 1 is a front view of the doll with 50 portions broken away to show the means for joining the head, arms and legs to the trunk;

Fig. 2 is a perspective view of the said joining means; and

Fig. 3 is a view of a modified form of 55 fastener in which the head is swiveled on the hook or open eye.

Referring to the drawing, 1 designates

the trunk, 2 the head, 3 the arms, and 4 the legs, all of which parts are made according to any approved method. The means for joining the arms to the body are the same as 60 the means for joining the legs thereto, such means comprising an elastic loop 5 and headed fasteners or buttons 6, the shanks or eyes 7 of which are open so as to constitute hooks for engaging with the ends of the 65 loops. These buttons lie outside the limbs at the ends joined with the body. The loops are normally under tension and are of such length as to extend entirely through the body and into the limbs and serve to yieldingly or flexibly connect the limbs with the 70 trunk. In attaching the limbs to the trunk a button is applied to one end of the loop, and then the loop is passed through the opening 8 of one limb, through the openings 75 9 of the body, thence through the opening 8 of the opposite limb, and then the other button is hooked onto the loop, a suitable instrument being engaged with the loop so that it can be easily threaded through the 80 limbs and body and pulled out far enough to permit the second button to be easily hooked on the loop, and after the button is hooked on, the pull on the elastic loop is removed, so that the same contracts and 85 draws the buttons close into the openings in the limbs. The head 2 has a hook 10 anchored therein, and this hook engages the middle of the upper elastic loop, which latter is pulled upwardly by a suitable instru- 90 ment far enough to permit the hook 10 to be engaged therewith, and when such engagement is made, the instrument is removed and the upper loop will be under sufficient tension to maintain the head and arms in 95 proper articulation with the body. The head may, however, be hooked to the lower elastic by lengthening the hook.

In Fig. 3, the head *h* of the fastener is 100 swiveled on the open eye or hook *i*.

The term "doll" as used herein is intended to cover figure toys generally which have hinged arms or legs.

From the foregoing description taken in connection with the accompanying drawing, 105 the advantages of the construction and method of operation will be readily understood by those skilled in the art to which the invention appertains, and while I have described the principle of operation, together with the article which I now consider to be the best embodiment thereof, I 110

desire to have it understood that the article shown is merely illustrative and that such changes may be made when desired as fall within the scope of the appended claims.

5 Having thus described my invention, I claim as new and desire to secure by Letters Patent:

1. In a doll, a body, an elastic element extending through the body and having its 10 extremities projecting from opposite sides thereof, limbs having ends presented to the body, there being apertures in said ends and into which the extremities of the elastic element extend, and fasteners having 15 eyes disposed in the said apertures and removably engaged with the extremities of the said element.

2. The combination of a doll body, limbs at opposite sides thereof, an endless elastic element extending through the body, and fasteners having heads disposed outside the 20 limbs and having open eyes extending into

the limbs and hooked into the ends of the elastic.

3. A doll body, arms at opposite sides 25 thereof, said body and arms having alining apertures, an elastic member extending through the body from one side to the other, fasteners having enlarged portions disposed outside the arms and hooks extending into 30 the arms and detachably engaged with the elastic member, and a head having a hook engaged with the middle of the elastic member.

4. Means for flexibly connecting the limbs 35 to the body of a doll, comprising an elastic having looped ends, and buttons having open shanks engaged with the looped ends of the elastic, the heads being swiveled.

5. Means for fastening limbs to the body 40 of a doll, comprising an endless elastic, and headed fasteners having hooks detachably engaging the ends of the elastic.

FREDERICK B. SCHULTZ.
